UNITED STATES PATENT OFFICE.

WILLIAM A. CHRYST, OF DAYTON, OHIO, ASSIGNOR TO THE DAYTON ENGINEERING LABORATORIES COMPANY, OF DAYTON, OHIO, A CORPORATION OF OHIO.

IGNITION SYSTEM.

Application filed December 17, 1920. Serial No. 431,435.

To all whom it may concern:

Be it known that I, WILLIAM A. CHRYST, a citizen of the United States of America, residing at Dayton, county of Montgomery, 5 State of Ohio, have invented certain new and useful Improvements in Ignition Systems, of which the following is a full, clear, and exact description.

This invention relates to ignition systems 10 for internal-combustion engines equipped with an electrically ignited fuel burner for auxiliary heating purposes and more particularly to engines having a plurality of spark plugs in each cylinder.

15 It is among the objects of the present invention to provide ignition for the engine spark plugs and burner spark plug without requiring induction apparatus additional to that required for engine ignition, and without interfering with the engine ignition.

Another object of the present invention is to simplify the distributing apparatus employed for distributing sparking impulses simultaneously to the plurality of spark 25 plugs in each of the several engine cylinders in correct sequence.

Other and further objects of the present invention will be apparent from the following description, reference being had to the 30 accompanying drawings, wherein a preferred embodiment of the present invention is clearly shown.

In the drawings:

Fig. 1 is a wiring diagram showing the 25 circuit connections between the various elements of the system;

Fig. 2 is a plan view of the ignition unit;

Fig. 3 is a part sectional view taken along the line 3—3 of Fig. 2; and

40 Fig. 4 is a plan view of the rotor element of the ignition unit.

By referring to Figs. 2 and 3, the ignition unit is shown comprising a main body portion 20 provided with inwardly projecting 45 lugs 21 which are adapted to support a plate 22. This plate in turn supports another plate 23 upon which are mounted the stationary contact standards of the circuit 50 interrupters described in detail hereinafter.

55 A pair of oppositely disposed holding clips 24 are secured to the main body portion 20 in any suitable manner, these clips being adapted to engage with ears 25 formed on the head 26 which in turn is adapted to rest on the upper edge of the housing 20.

This head 26 is provided with a plurality of circularly arranged terminals 27. A central terminal 28 is provided in the head portion 26, having a spring pressed contact 29 associated with its inner end, for purposes 60 hereinafter described. Another terminal 30 is arranged adjacent to the terminal 28, the inner end of which is connected to a circular track 31. The function of these devices will be described hereinafter.

65 An engine driven shaft 32 projects upwardly through the housing 20 and plates 22 and 23, said shaft having the cam element 33 secured thereto in any suitable manner. The shaft 32 has a reduced portion 34 above the cam 33 over which the rotor element 35 is adapted to fit and be driven thereby. This rotor element 35 comprises a main body portion 36 and an angularly arranged rib portion 37. In one end of this angularly arranged rib portion 37 there is a contact button 38. A spring element 39 holds button 38 in electrical connection with a metal strip 40 which projects to the center portion of the rotor and is adapted to be engaged 70 by the spring pressed contact 29 of the terminal 28. Another rotor button 41 is carried at the opposite end of the rib portion 37 and is pushed outwardly by a spring 42. This button is connected to an outwardly 75 spring pressed brush 43, by means of a connector strip 44, said brush 43 in turn being adapted to engage the circular track 31 connected to the terminal 30 eccentrically arranged to the terminal 28 as has been mentioned heretofore.

80 By referring to Fig. 1, the interrupter elements of the ignition unit are clearly shown. These interrupters include movable arms 50 and 51 fulcrumed to, but insulated from, the plate 23 at the one end, the other end carrying contacts 52 and 53 respectively. These 85 movable arms 50 and 51 are provided with cam riding blocks 54 and 55 which, when the cam 33 is in operation, will tend to operate said arms causing the contact elements 52 and 53 to disengage with their respective stationary contacts 56 and 57, respectively. As can be seen in the drawings, the cam riding block 55 is comparatively narrower than the cam riding block 54 for purposes which 90 will be described in detail hereinafter. The movable arms 50 and 51 are connected to the ignition unit terminals 58 and 59 by means 95 of flat springs 60 and 61, respectively, these 100 105 110

springs also functioning to hold said arms against the cam 33.

The operation of the system will now be set forth. As has been mentioned hereinbefore, it is the object of the present invention to provide spark impulses for the various engine spark plugs and the burner plug, without requiring additional induction means or coils necessary for the engine operation, 10 without affecting the efficient operation of the same. As can be seen in the drawings, and more particularly in Fig. 1, an engine 65 is provided, having cylinders 66 which are provided with sets of spark plugs 67 and 68. 15 These spark plugs of the various cylinders are connected to their respective terminals 27 of the ignition unit. When it is desired to operate the engine, the switch 70 is closed, permitting current to flow from the battery 20 71 to the point 72, thence the current will branch through the lead 73, primary windings 74 of ignition coil 75, wire 76 to the terminal 58, spring 60, contact arm 50, across the contacts 52 and 56 and back to the battery via the ground connections 80. From the point 72, current will also branch through the wire 77, primary winding 78 of ignition coil 79, wire 81, terminal 59, spring 61, contact arm 51, across the contacts 53 and 25 57 and back to the battery via the ground connections 80. It is understood, of course, that to permit this flow of current, the cam element 33 is in such a position, that the contacts 52 and 56, and 53 and 57, respectively, will be closed. As soon as the cam 33 rotates to open the contacts, as is shown in Fig. 1, sparking impulses will be induced in the secondary winding 82 of ignition coil 75, which will be directed through the wire 40 83 to the terminal 30, circular track 31, brush 43, secured to the rotor 35, as has been explained heretofore, connecting strip 44 to the rotor button 41, and thence to the various terminals 27, alternates of which are 45 connected to the set of spark plugs 67 of the engine cylinders 66 as is shown in the drawings. The relative operation of the cam and the interrupter arm 50 to the rotor distributor element contacting with the alternate 50 terminals 27, connected to the set of spark plugs 67 of the engine 65, will provide sparking 55 impulses directly to these spark plugs.

Interruption of the circuit through the primary winding 78 of the ignition coil 79 will cause sparking impulses to be induced in the secondary winding 84 of said ignition coil. Said impulses will then be directed via the wire 85 to the spark plug 86 of the burner 60 87 which, as has been mentioned in the opening paragraph of this application, is adapted to burn fuel and act as an auxiliary heater, shown in the present drawings as heating the intake manifold 88 of the engine 65. After the spark impulse has jumped the gap of the 65 spark plug 86, it will then be directed along

the wire 89 to the central terminal 28 of the distributor unit, thence to the spring pressed contact 29, connector strip 40, rotor button 38 to the alternate terminals 27 which are connected to the set of spark plugs 68 of the 70 various cylinders 66 of engine 65. As can be clearly seen by this description the spark plugs 68 are in series connection with the spark plug 86 of the burner 87 and if no special arrangement would be provided the 75 sparking impulses through these spark plugs 68 would be inferior to and less efficient than the sparking impulses provided at the spark plugs 67. In order to compensate for this without changing or affecting the induction 80 apparatus used for providing the regular engine ignition, the cam riding block 55 of the circuit interrupter, which provides sparking impulses for both engine and burner spark plugs, is narrower than the 85 block used in connection with the other interrupter. This permits the contacts 53 and 57 of the engine spark plug and burner spark plug ignition apparatus, to be closed for a longer period than the other interrupter, thereby permitting the ignition coil 79 to become energized to a greater degree than the ignition coil 75 and thereby tend to provide a spark of greater intensity for the set 90 of spark plugs 68 than that furnished by the set of spark plugs 67. It will, of course, be understood that with the burner spark plug 86 in series with the spark plugs 68, the final sparking impulses at the engine spark plugs 68 will be practically equal to that of the spark plugs 67, due to the energy consumed in furnishing a spark at the plug 86.

As has been mentioned heretofore, the alternate terminals 27 are connected, one set to the set of spark plugs 67, the other set to the set of spark plugs 68. This arrangement of terminals in connection with an angularly arranged rotor, permits a single ignition unit or distributor unit to be used where heretofore two units have been employed for distribution to two sets of spark plugs in engine cylinders. The rotor element, as is shown in Fig. 4, has one button displaced 30° from the central line of the other button, thus when 12 terminals are 105 used, and arranged equidistant in a circular manner, and interrupters are employed which will cause simultaneous sparking 110 impulses at every 60° of the cam, the sparking impulses caused by these interrupters may be concurrently directed to two different sparking devices, thus eliminating the necessity of providing two separate and distinct distributor heads for obtaining the 115 desired results.

As is shown in Fig. 1, each of the sets of contacts 52 and 56, and 53 and 57, are provided with condensers 90 and 91, respectively, for purposes well known in the art.

While the form of mechanism herein 120

shown and described constitutes a preferred form of embodiment of the invention, it is to be understood that other forms might be adopted, all coming within the scope of the 5 claims which follow.

What I claim is as follows:—

1. In an ignition system, the combination with an engine having a plurality of sets of spark plugs and a fuel burner having a spark 10 plug; of a current source; a plurality of ignition coils; means for distributing in recurrent sequence the impulses of one coil to a set of engine spark plugs and for currently distributing in recurrent sequence 15 the impulses of another coil to another set of engine spark plugs and to the burner plug; and timing mechanism for so controlling the passage of current to the coils that impulses of substantially equal intensity 20 will be delivered to the sets of engine spark plugs, while the burner plug is being provided with impulses.
2. In an ignition system, the combination with an engine including a cylinder having 25 a plurality of plugs, and having a fuel burner provided with a plug; of a plurality of ignition coils; a current source; means for connecting one coil with one of the engine plugs; means for connecting another 30 coil with another engine plug and with the burner plug; and timing mechanism for so controlling the passage of current to the coils that impulses of substantially equal in- 35 tensity will be delivered to the sets of engine spark plugs, while the burner plug is being provided with impulses.
3. In an ignition system, the combination with an engine having a plurality of sets of spark plugs; of a source of current; a 40 plurality of ignition coils; engine operated

interrupters for connecting the source of current to the ignition coils for providing a plurality of sets of sparking impulses in recurrent sequence; a unitary distributing means for directing each set of sparking impulses to a respective set of engine spark plugs in recurrent sequence; a fuel burner; and a burner spark plug connected between the distributing means and one of the ignition coils whereby sparking impulses will 50 be provided to both the burner and one set of engine spark plugs concomitantly.

4. The combination with a multicylinder internal-combustion engine having spark plugs and a fuel burner having a spark 55 plug, of ignition means connecting the fuel burner plug in series with a part only of the engine plugs; and including instrumentalities for producing sparking impulses of substantially the same intensity at all the 60 engine spark plugs.

5. The combination with a multicylinder internal-combustion engine having spark plugs and a fuel burner having a spark 65 plug, of ignition means connecting the fuel burner plug in series with a part only of the engine plugs; and including instrumentalities for producing sparking impulses of substantially the same intensity at all the engine spark plugs, and a single 70 distributor for distributing the sparking impulses in recurrent sequence to the engine spark plugs.

In testimony whereof I hereto affix my signature.

WILLIAM A. CHRYST.
